UNITED STATES PATENT OFFICE.

SPENCER OTIS, OF BARRINGTON, ILLINOIS, ASSIGNOR TO THE LOCOMOTIVE TERMINAL IMPROVEMENT COMPANY, OF CHICAGO, ILLINOIS, A CORPORATION OF MAINE.

LOCOMOTIVE TERMINAL WITH STEAMING EQUIPMENT.

Application filed January 10, 1923. Serial No. 611,710.

This invention relates to terminals in which a locomotive may be treated for purposes of renovation and restoration to service, and particularly to a locomotive terminal 5 equipped for washing out and refilling the boiler of a locomotive, and in which locomotives, after such treatment, require to be restored to the power of self propulsion.

The object of the invention is to provide 10 means whereby such a terminal may restore a locomotive to service in a greatly reduced time, and at a material saving in expense as compared with practice heretofore followed, so that the stall occupied by the locomotive 15 can be relinquished to a succeeding locomotive, and the restored locomotive can be rendered available for its assigned track in the least possible time; also to provide the terminal with facilities for maintaining the 20 locomotive at steaming pressure at a minimum of expense, even after it leaves the renovating stall and until it leaves the terminal for its assigned track.

It has long been the practice to introduce 25 water into a steam boiler through means of a steam injector, in which steam initially at high velocity and condensed into water without reducing its velocity takes up the feed water and overcomes the internal resistance 30 of the boiler. It has also been proposed to release steam under pressure, from an external source, into the lower part of a partly filled boiler, and to permit the steam to give off its heat to the water of the boiler and in 35 the course of time develop boiler pressure. But these methods, aside from having to do with the treatment of boilers that are in operation and already supplied with a complement of water, are relatively slow and in- 40 sufficient and afford no substantial assistance in solving the problem of the present invention, which is to restore the steam boiler within a minimum of time from a state of evacuation to a condition of full water 45 charge at steaming temperature and with internal working pressure.

The present invention proceeds upon the principle of providing the locomotive terminal with not only usual means for blowing 50 off the contents of a boiler, salvaging the heat units of the blown off products, washing out the boiler, and supplying filling water to the same, but in addition thereto, providing means for supplying the filling water at the

highest available temperature and under a 55 head of pressure that will cause it to enter the boiler not only at the beginning when there is no internal boiler resistance, but throughout the filling operation during which, under the conditions herein described, the pressure 60 is gradually building up, and until the end point of the filling operation when the pressure may be as high as one hundred pounds or more, and combining with this means for supplying hot water under pressure, a super- 65 heated steam supply which will be combined with the water supply at or before the point of entering the boiler in a manner to boost the entrance of the water into the boiler and the temperature of the water so entering; the 70 steam supply being continued throughout the filling operation in a manner to have the boiler under internal pressure at the time the filling is complete, and to develop from the added steam, shortly after the filling 75 ceases, a pressure over the water which will enable the locomotive to leave its stall under its own pressure, with or without kindling of the newly laid fire.

Preferably the terminal will be equipped 80 with means for keeping up the supply of steam at a point outside the renovating stall so that steam pressure can be maintained in the locomotive while it is waiting to be assigned to a service track. Under some circumstances, 85 the fire may be ignited during the filling operation and steam development from the external sources described, so that the time of attainment of steaming pressure will be still further reduced; but preferably the fire will 90 be ignited at such time in relation to the expected departure of the locomotive from the waiting stand as will insure the maintenance of steam pressure after the locomotive leaves such stand. Steam for artificial blow- 95 ing may be supplied to the stack in accordance with established practice, and steam supply means at the renovating station will preferably be equipped for acting upon the boiler discharge at the time the boiler is being 100 evacuated and particularly during the latter part thereof for the purpose of cutting down the time required for emptying the boiler, the steam so supplied being salvaged along with the heat units from the blown off prod- 105 ucts.

A flow meter or other means may be employed by which the consumption of steam

through the steam pipe will be compensated by increased generation in the local plant.

In the accompanying drawings—

Figure 1 is a schematic view of a locomotive terminal station embodying the several features of the invention, the locomotives being shown in the renovating stall and parking station.

Figure 2 is a section on the line 2^x—2^x of Figure 1 on a greatly enlarged scale; and

Figure 3 is a detail view on a larger scale of the equipment at the renovating stall.

Figure 4 is a detail view showing the hose connections of Figure 3 shifted to cause blow-off from the base of the boiler to take place through the mixing box to the blowoff drop, and to be boosted by the use of live steam.

Referring to Figure 1, A represents a main track, B a series of spur tracks leading therefrom, C a locomotive terminal house, D a series of renovating stations in said locomotive house, E a series of parking or waiting stations adapted to be assumed by locomotives under self propulsion by steam pressure developed in them at the renovating stations, F a series of spur tracks leading from the parking stations, and G a branch track connecting all of the spur tracks F, through switching tracks H and I, in either direction, 30 with the track A. In addition to the foregoing, the locomotive terminal is equipped with blowoff, washout, refilling, and steam supplying apparatus now to be described, and it may be supplied with any other accessory apparatus or equipment such, for instance, as a coaling station K.

Referring more particularly to Figures 2 and 3, 1 represents a blowoff pipe adapted to receive blown off products from a locomotive boiler 2, through a pipe 1^a adapted to communicate with a steam dome, as through hose 1^b, or with the lower portion of the boiler through a hose 1^c, as may be desired; this blowoff pipe being connected to deliver the blown off products to a separator 3, whence the steam constituent escapes through a pipe 4 to a condenser 5 and thence, accompanied by an increment of water which reaches the condenser through the pipe 6 (Fig. 3), flows through a pipe 7 to the filling tank 8; and the water constituent of the blown off products being delivered through pipe 9 to washout tank 10. Water from washout tank 10 is advanced by a pump 11 (Fig. 3) through a pipe 12 to feed the drop 13 at the post 14 of the locomotive renovating station. Water from filling tank 8 is advanced by pump 15 through pipe 16 to supply a drop 17 at said post 14.

In addition to the washout and refill water supply pipe, the terminal is equipped with a live steam pipe 18 leading from any suitable stationary boiler 19 where steam can be economically and constantly generated, and this live steam pipe 18 supplies a steam drop 20 at the post 14. Steam drop 20 and filling

water drop 17 meet a combined injector and heating box 21 from which a filling pipe 22 leads to the boiler 2 into which the heating box discharges, preferably at the front boiler leg 23 in front of the fire box 24.

In treating a locomotive in a terminal equipped as herein described, the procedure is as follows: With the blowoff pipe 1^a connected to the steam dome by means of hose 1^b, as shown in full lines in Figures 2 and 3, steam may be discharged from the locomotive, under pressure of the locomotive boiler,

from a point above the water level thereof, and passed to the filling tank under any of the conditions long recognized in this art, for instance, by sending it to the tank by way of the condenser 5; this steam evacuation being followed by gravity discharge of the water and sludge through the blowoff cock 23. Or,

the initial discharge of the boiler contents may be conducted through an extension 1^c of the pipe 1^a, connected to the blowoff cock at 23, so that internal boiler pressure will assist in evacuating the water and sludge; all of said products being passed to the separator 3 whence the volatiles escape to the condenser 5 and thence to the filling tank 8; and the remnant liquids ultimately going to the washing tank 10. Or, as shown in Fig. 4 the extension 1^c, shown in dotted lines in Figure 3,

may be connected to the mixing box 21, and the connecting hose 22 may be made to lead from the blowoff cock 23 to the nozzle 21^a of said mixing box and the valve 17^a closed and the valve 17^b opened, so that the liquid products pass from the locomotive boiler through the mixing box 21, and thence through the extension 1^c and blowoff drop 1^a into the blowoff pipe 1 so that by opening the high pressure steam pipe 20 the blowoff may be boosted, either initially or at such time in the procedure as may be necessary to keep up the rapidity of discharge. Having thus evacuated the boiler and performed any washing service that may be necessary by any suitable method, the boiler is ready to be filled, to

which end, connection 22 is restored to the position shown in Figures 2 and 3, the connection 1^b is removed from the steam dome, filling water drop 17 is opened to the mixing box 21, the high pressure steam pressure drop 20 is likewise opened, and a mixture of water and steam, or water first followed by a mixture of steam and water afterwards, will flow into the locomotive boiler from the stationary boiler under conditions that induce boiler circulation, with consequent distribution of heat, and rise of steam within the boiler, thereby further equalizing boiler temperatures and preventing undue stresses in the plates. By the time the water level in the boiler 2 reaches the first gauge 25, the pipe 17 will be closed and steam alone then permitted to flow into the boiler, rising through the water and accumulating above the water level

130

until internal pressure is developed. This will be continued until the pressure is sufficient to enable the locomotive to leave a renovating stall D under its own power and pass 5 to a parking station E, where it will again be connected with the drop pipe 20 of steam pipe 18 through a hose 22, and the flow of steam into the boiler will be continued at a rate just sufficient to keep up the pressure in the 10 boiler and have the locomotive ready to proceed to its assigned track at any time. While at the station D, a smoke jack 28 may be applied to the stack 29 and a fresh fire ignited in fire box 24 to assist in getting up steam; or 15 the lighting of the fire may be omitted at renovating station D, and after the locomotive reaches the waiting station E equipped with smoke jack 28, and at such time previous to the expected departure of the locomotive 20 as will insure a hot surface to the fire at the time the locomotive is ready to depart, the fire may be ignited.

The effect of discharging filling water into the boiler at the point 23, and particularly 25 when the motion of the water is greatly accelerated by the propelling power of the steam jet in the combined injector and heating box 21, is to establish circulation of the accumulating water throughout the interior 30 of the boiler, with the result that the temperature of the boiler is raised uniformly throughout and temperature strains are avoided. This result of heating the boiler uniformly throughout will also be contributed 35 to by the steam and vapor rising from the incoming mixture of steam and water even at the beginning of the filling operation.

The connection 1^e for blowing off water from the boiler is adapted to be attached to 40 the injector box 21 so that discharge from said box will be delivered through the connections 1^e and 1^a to the blowoff pipe; and the connection 22 from the low part of the boiler is adapted to be attached to the connection 21^a, and through said connection deliver water from the boiler into the injector 45 box 21, whence it will pass through connections 1^e and 1^a to the blowoff pipe; and if live steam pipe 20 be opened at this time, the flow 50 of blowoff water will be accelerated and the time required for evacuation of the boiler correspondingly reduced. Inasmuch as the

heat units of the steam used for this purpose are recovered in the condenser 5 and delivered to filling tank 8, this method of procedure is 55 economical. Ordinarily, in blowing off the boiler, water will be evacuated from the point 23 directly into connection 1^e, and thence through connection 1^a to the blowoff pipe so long as internal boiler pressure is sufficient to insure a rapid evacuation of the boiler. But when the boiler pressure drops to a point which greatly slows down the flow of water from the boiler, the connections will be shifted 60 in the manner described, and evacuation 65 of the remainder of the water will be boosted by the steam jet.

30 represents a flow meter or other suitable means for the steam line 18 having connection 31 with a damper 32 whereby it may maintain pressure in the boiler 19 commensurate 70 with consumption of steam on the line 18.

I have established by experiment that great economy in coal consumption will be achieved by equipping a locomotive terminal in the 75 manner herein described, and an important feature of the invention contributing to this result is the means for supplying water at high temperature and under pressure, and means for delivering to said water high pressure steam under conditions which boost the 80 flow of water into the boiler, raise the temperature of the water so introduced and gradually develop steaming pressure within the boiler.

I claim:

1. In a locomotive terminal, a blowoff line, means for connecting the lower portion of a locomotive boiler with said blowoff line, a source of high pressure steam, means adapted 90 to connect said source of steam to said blowoff line in relation to boost the evacuation of the locomotive boiler through said line.

2. In a locomotive terminal, a blowoff line, means for connecting the lower portion of a locomotive boiler with said blowoff line, a source of high pressure steam, means adapted 95 to connect said source of steam to said blowoff line in relation to boost the evacuation of the locomotive boiler through said line, and means for salvaging heat units of the blown off products and of the steam supplied to the blowoff line.

SPENCER OTIS.
